HANDS FREE TELEPHONE SUBSET

Gino Natali, Milan, Italy, assignor to International Standard Electric Corporation, New York, N.Y., a corporation of Delaware

Filed Nov. 19, 1962, Ser. No. 72,541

Term of patent 14 years

(Cl. D26—14)

FIG. 1.

FIG. 3.

FIG. 2.

FIG. 1 is a front, top and right side perspective view of a hands free telephone subset, showing my new design with its cover in open position;

FIG. 2 is a right side elevational view, with the cover in closed position, the opposite side being substantially a mirror image thereof; and

FIG. 3 is a top plan view thereof with the cover in closed position.

The dial shown in broken lines is conventional. The dominant features of my new design are shown in solid lines in the drawing.

I claim:

The ornamental design for a hands free telephone subset, as shown and described.
